UNITED STATES PATENT OFFICE.

CHARLES J. KAUFMANN AND THOMAS A. SMITH, OF AUSTIN, MINNESOTA, ASSIGNEES
TO GEO. A. HORMEL & COMPANY, OF AUSTIN, MINNESOTA, A CORPORATION OF MIN-
NESOTA.

MACHINE FOR SPLITTING PIGS' FEET.

Application filed October 29, 1927. Serial No. 229,655.

This invention relates to new and useful improvements in machines for splitting pigs' feet.

An object of the invention is to provide such a machine comprising a rotary knife and a conveyer having means for holding and supporting the pigs' feet in such a manner that when they are fed against the knife blade, they will be split longitudinally. 5
10 A further object of the invention is to provide a machine for splitting pigs' feet comprising a frame having a rotary knife mounted in the upper portion thereof beneath which a conveyer chain is arranged 15 which has demountably secured thereto a plurality of V-shaped holders, each adapted to support a pig's foot and to feed it longitudinally against the knife blade, each holder being provided with anti-friction 20 rollers adapted to travel upon guide rails which function to provide a support for the holders.

A further object is to provide such a machine comprising a conveyer chain having a 25 plurality of substantially V-shaped holders detachably secured thereto, each having a soft metal bottom upon which the pigs' feet are supported, and the rotary knife of the machine being adjustably mounted with respect to said holders whereby the cutting 30 edge thereof may be positioned to substantially engage the soft metal bottom of the holders, thus insuring a smooth, clean cut.

The particular object of the invention 35 therefore is to provide a simple and inexpensive machine for splitting pigs' feet, comprising a rotary knife having a smooth cutting edge whereby the pigs' feet may be split longitudinally without waste.

40 Other objects of the invention will appear from the following description and accompanying drawings and will be pointed out in the annexed claims.

In the accompanying drawings there has 45 been disclosed a structure designed to carry out the various objects of the invention, but it is to be understood that the invention is not confined to the exact features shown as various changes may be made within the 50 scope of the claims which follow.

In the accompanying drawings forming part of this specification:

Figure 1 is a view in side elevation of the improved machine, partially broken away to

show the relative positions of the knife blade 55 and holders as the latter pass beneath the knife;

Figure 2 is a cross sectional view on the line 2-2 of Figure 1;

Figure 3 is a plan view of one of the 60 holders removed from the conveyer chain; and

Figure 4 is a cross sectional view on the line 4-4 of Figure 3, showing the position assumed by a pig's foot when positioned in 65 a holder and engaged by the knife.

The novel apparatus featured in this invention comprises a conveyer chain 2 mounted upon suitable sprockets 3 and 4. The sprocket 3 as carried by a shaft 5 mounted 70 in suitable bearings secured to an extension 6 of the main frame 7, as shown in Figure 1. This shaft is driven from a motor 8 through a train of gears 9, supported upon the horizontal member 11 of the frame extension 6. 75 The motor 8 may be supported upon a suitable bracket 12 secured to the main frame 7 as shown in Figure 2. The sprocket 4 is mounted upon a shaft 13 which is borne by bearings 14, adjustably mounted on brackets 80 15 to provide means for taking up slack in the conveyer chain 2.

A feature of this invention resides in the novel means provided for splitting the pigs' feet longitudinally, and, without waste. 85 Machines of this type now in use are generally provided with saws for splitting the pigs' feet. These have been found more or less objectionable because of the waste caused by the saw teeth carrying away a portion of the 90 pig's foot during the cutting operation. It is therefore desirable that means be provided whereby the pigs' feet may be split longitudinally with a clean smooth cut, thus eliminating practically all waste, resulting in increased efficiency and economy of the apparatus. 95

The novel structure featured in this invention comprises a circular knife 16 mounted upon a shaft 17 above the conveyer chain 2. 100 The shaft 17 is mounted in bearings 18 and 19, adjustably secured to the uprights 7 of the main frame as shown in Figure 2. The uprights 7 are slotted as indicated at 21 and screw eyes 22 are secured to the bearings 18 105 and 19 and extend upwardly through brackets 23, terminally provided upon the uprights 7. Hand wheels 24 are received in threaded

engagement with the screw eyes 22 to provide means for adjusting the circular blade 16 with respect to the bottom surfaces 25 of the holders 26. The shaft 17 is preferably driven by a silent chain 27 connected with the motor 8, as indicated at the left hand side of Figure 2. A suitable fly-wheel 20 is preferably mounted upon the shaft 17, as shown in Figure 2.

10 Another feature of the invention resides in the novel construction of the holders 26 which function to provide supports for the pigs' feet and to convey them against the knife blade, as shown in Figure 1. Each of these holders 15 is substantially U-shaped in cross-section and is preferably constructed of boiler plate having trunnions 29 provided on each side thereof adapted to receive flanged rollers 31. These rollers are adapted to travel upon 20 guide rails 32, secured to the main frame of the machine as shown in Figure 2. The ends of the holders 26 are open, as indicated at 33 in Figures 2 and 4, to provide clearance for the knife 16 when the holders pass therebeneath. 25 The bottom of each U-shaped holder is covered with a suitable soft metal such, for example, as lead or babbitt. In operation, the blade 16 is adjusted so that the cutting edge thereof substantially engages the top 30 surface 25 of the soft metal provided in the bottom of the holders. Thus, when the holders successively pass beneath the knife, the pigs' feet positioned therein will be engaged by the knife which will split or sever them 35 lengthwise as shown in Figures 1 and 4. As a result of the bottoms of the holders 26 being of comparatively soft metal, the cutting edge of the knife blade may be substantially engaged therewith without danger of becoming dulled.

40 The holders 26 are preferably detachably secured to the conveyor chain 2 to permit removal therefrom for repairs or replacement, when necessary. As here shown, the holders 45 are connected with the conveyor chain by means of brackets 35 having their upper ends seated against the sides of the U-shaped holders 26 and secured thereto by means of bolts 36. The lower ends of the brackets 35 may 50 be integrally formed with the links 37 of the conveyor chain. Guide rails 38 are also provided at the lower portion of the frame 7 adapted to be engaged by the rollers 31 to relieve the conveyor chain of the weight of the 55 holders, upon its return run.

In order to provide a smooth, clean cut, 60 water is preferably sprayed or discharged onto the upper portion of the rotary knife blade 16. Water may be delivered to the knife blade through a pipe 38, having a connection with a source of supply, not shown. A valve 39 is provided for controlling the supply of water to the knife. A housing 41 preferably encloses the upper portion of the 65 rotary knife 16 to prevent it from throwing

or spraying water about the machine while in operation. The lower wall 42 of this housing is spaced relatively close to the upper edges of the holders 26, and functions as a guard to prevent the pigs' feet from being 70 thrown out of the holders, when engaged by the knife. In actual practice, it has been found that this guard is of little use as the 75 pig's foot, when being split by the knife, scarcely moves with respect to the holder wherein it is positioned. Nevertheless, the plate 42 guards against any possible danger of the foot being thrown out of the holder, should it be engaged by the knife in an abnormal manner.

80 In the operation of this novel machine, a pig's foot may be placed in each holder 26, whereby they will be successively moved into engagement with the rotary knife blade and severed lengthwise, after which they will be 85 discharged from the upper end of the machine onto a suitable receiving means, such as a bin or table, not shown. The conveyor chain and holders are preferably arranged at an incline, as shown in Figure 1, for the sake 90 of convenience. By thus arranging it, the receiving end of the machine will be positioned above the floor at a height convenient for the operator to place the pigs' feet in the holders, and, as a result of the discharge end 95 of the apparatus being elevated, sufficient room is provided therebeneath to accommodate a truck or other receiving means, which might not be possible if the conveyor chain and holders were arranged horizontally. 100 Also, as a result of the holders being arranged at an incline, the water discharging over the rotary knife from the pipe 38, is more readily drained from the holders. The angle of 105 the chain and holders therefore may be varied and, if desired, may be operated in a horizontal plane without departing from the scope of the invention.

We claim as our invention:

1. A machine for splitting pigs' feet, comprising a rotary knife, a conveyor chain, a plurality of holders secured to said chain and each adapted to support a pig's foot, said holders having their opposite ends open to receive said rotary knife, and each holder further having a soft metal bottom adapted substantially to be engaged by the cutting edge of said rotary knife, whereby when the pigs' feet are fed against said knife by movement of said holders, the pigs' feet will be 110 split longitudinally with a clean smooth cut.

115 2. A machine for splitting pigs' feet, comprising a revolving cutting blade, holders adapted to receive the feet each having a bottom of comparatively soft material upon 120 which the pigs' feet are placed, and means for feeding said holders successively to said blade whereby the feet will be split or divided longitudinally.

125 3. A machine for splitting pigs' feet, com-

- prising a revolving cutting blade, holders having flaring side walls, end walls on each holder between which and said side walls the feet are held, said holders having means beneath the normal position of the feet adapted substantially to be engaged by the blade, whereby the blade may cut entirely through the feet, and means for successively feeding said holders and feet to said blade.
- 10 4. A machine for splitting pigs' feet, comprising a cutting blade, a series of holders each adapted to receive a pig's foot, means for guiding said holders, means for feeding them successively to said blade, and an elongated member in each holder permitting said blade to pass entirely through each foot in splitting the same longitudinally, and whereby a smooth clean cut is obtained.
5. A machine for splitting pigs' feet, including a revolving splitting blade, holders having walls between which the feet to be split are placed, each holder having a comparatively soft material in the bottom there-
- of under and adjacent the foot to be split, said holders having suitable guides and means for directing them successively toward said splitting blade, the soft material in the bottom of each holder permitting said blade to pass completely through each foot during the splitting operation.
- 25 6. A machine for splitting pigs' feet, comprising a rotary cutter, a driving means therefor, an endless conveyer, a plurality of holders secured to said conveyer in spaced relation, each holder having outwardly flared walls, a soft metal bottom in each holder upon which the pigs' feet are placed, said soft bottom being adapted to be engaged by the cutting edge of said cutter whereby the pigs' feet are cut clean through, and means for spraying 35 said cutter to prevent particles of meat from adhering thereto, when in operation.
- 30
- 35
- 40

In witness whereof, we have hereunto set
or hands this 20th day of October, 1927.

CHARLES J. KAUFMANN.
THOMAS A. SMITH.
